UNITED STATES PATENT OFFICE.

MARY A. WILLIAMS, OF NEW YORK, N. Y.

DESIGN FOR A PETTICOAT.

58,414.

Specification for Design.

Patented July 12, 1921.

Application filed March 15, 1920. Serial No. 366,111. Term of patent 14 years.

To all whom it may concern:

Be it known that I, MARY A. WILLIAMS, a citizen of the United States, residing at New York city, in the county of New York and State of New York, have invented a new, original, and ornamental Design for Petticoats, of which the following is a specification, reference being had therein to the accompanying drawing.

This invention relates to a design for petticoats, as illustrated in the accompanying drawings, in which—

Fig. 2 is a perspective view of the petticoat in its position as worn.

Fig. 3 is a sectional view on the line 3—3, of Fig. 1.

I claim:

The ornamental design for a petticoat, as shown.

In testimony whereof, I hereunto affix my signature.

MARY A. WILLIAMS.
